DESIGN FOR A FISHING LURE

Russell S. Powell, Takoma Park, Md.

Application May 25, 1938, Serial No. 77,377

Term of patent 7 years

To all whom it may concern:

Be it known that I, Russell S. Powell, a citizen of the United States of America, residing at Takoma Park, in the county of Prince Georges and State of Maryland, have invented a new, original, and ornamental Design for a Fishing Lure, of which the following is a specification, reference being had to the accompanying drawing, forming part thereof.

I claim:

The ornamental design for a fishing lure, as shown.

RUSSELL S. POWELL.
